GUIDE CONTROL MECHANISM

William C. Nash, Neenah, Wis., assignor to Gilbert & Nash Company, Neenah, Wis., a corporation of Wisconsin

Application January 24, 1936, Serial No. 60,590

2 Claims. (Cl. 74—241)

This invention relates to improvements in paper making machine equipment and refers specifically to a device which simultaneously guides a paper machine paper forming wire or screen and maintains the wire or screen at a desired degree of tension.

The objects and advantages of my invention will be apparent from the accompanying drawings and following detailed description.

10 In the drawings, Fig. 1 is a side elevational view of my improved device in operative position with respect to a paper forming wire or screen.

Fig. 2 is a top plan view of the device shown in Fig. 1.

15 Fig. 3 is a sectional view taken on the line 3—3 of Fig. 2.

Fig. 4 is a sectional view taken on the line 4—4 of Fig. 1.

20 Fig. 5 is a fragmentary, elevational view illustrating the spring for actuating the shifting levers when the edge of the web moves laterally away from the palm or feeler.

25 Referring in detail to the drawings, 1 and 2 indicate vertically positioned posts or pillars which are disposed on opposite sides of a paper making machine. A paper forming wire or screen 3 passes between said pillars. A block or sleeve 4 may be slidably positioned upon the pillar 1 and in like manner a block or sleeve 5 may be slidably positioned upon the pillar 2. An extension 6 is connected to or formed integral with the sleeve 4 and supports at its outer end a substantially square frame 7, the extension 6 being connected to said frame by means of bolts 8 or the like. In 30 like manner the sleeve 5 carries an extension 9 which, in turn, supports frame 10. A screw 11 is connected at each of its ends to opposite sides of the frame 7, said screw being longitudinally immovable and also non-rotatable. A double 35 faced ratchet wheel 12 may be rotatably mounted upon screw 11, the bore of the ratchet wheel being provided with threads which are engageable with the threads upon screw 11. In view of the fact that the screw 11 is immovable with respect 40 to the frame 7, rotation of the ratchet wheel 12 will result in movement of the wheel 12 axially along the length of screw 11.

45 A collar 13 may be positioned upon screw 11 on each side of the ratchet wheel 12, said collar being freely positioned upon the screw. A standard 50 14 may support each collar 13, said standards being secured to or being formed integral with block 15 which may be slidably mounted upon the lower side 16 of the frame 7. Plates or clamps 55 17 and 18 may be secured as by means of bolts

19 to the block 15, said plates embracing the edges of the side 16 of the frame 7. A journal box 20 may be positioned adjacent the lower face of the side 16 and may be secured, as by means of bolts 21 to plates 17 and 18. The journal box 20 carries a bearing 22 in which one end of the shaft of roll 23 is journaled. It can readily be seen that the block 15 and journal 22 can be moved as a unit with respect to the frame 7, and that movement of the ratchet wheel 12 will impart 10 movement to the block 15 and hence, the bearing 22.

20 Roll 23, as will be hereinafter more fully described, is in contact with the wire or screen 3 and serves to guide said screen and maintain 15 the same in a taut condition. In view of the fact that the screen 3, during operation of the paper making machine, is in translatory motion and since roll 23 is in contact with said screen, 25 said roll will be rotated by motion of the screen. A gear box 24 may be mounted adjacent bearing 22 and is adapted to cover a pinion which is mounted upon the end of the roll shaft and a meshing gear which may be mounted upon the shaft 25. Therefore, motion of the roll 23 imparts motion of rotation to the shaft 25 at a reduced speed. An eccentric pin 26 may be mounted upon the end of the shaft 25 and may serve as a pivot pin for connecting rod 27 which may be connected to said pin at one of its ends. The opposite end of rod 27 is pivotally connected by means of pin 28 to arm 29 which, in turn, is rigidly connected to shaft 30. A bracket or standard 31 may be mounted upon plate 17 and the upper end of said bracket supports sleeve or bearing 32 30 in which the shaft or pin 30 is journaled. The opposite end of the shaft or pin 30 is rigidly connected to arm 33 which, in turn, is pivotally connected by means of pin 34 to the upper end of the U-shaped member 35.

40 It can readily be seen that when roll 23 is driven by its contact with screen 3, shaft 25 will be rotated and reciprocating motion will be imparted to shaft 28. This reciprocation rocks arms 29 and 33 and, hence, a substantially vertical reciprocating motion is imparted to the U-shaped member 35. One arm 36 of the U-shaped member 35 carries a pawl 37 which is disposed adjacent one face of the ratchet 12. The opposite arm 33 also carries a pawl 39 which is disposed adjacent the opposite face of the ratchet wheel 12. The ratchet teeth upon the opposite faces of the ratchet wheel 12 are so constructed and the pawls 37 and 39 are so positioned with respect to said ratchet teeth that engagement of pawl 55

37 with the ratchet teeth upon the adjacent side of the wheel 12 will cause said wheel to be moved upwardly as viewed in Fig. 1. Engagement of the pawl 39 with the ratchet teeth upon the 5 adjacent side of the wheel 12 will cause movement of the wheel 12 in a downwardly direction as viewed in Fig. 1. As will be hereinafter more fully described, the normal position of the U-shaped member 35 is such that neither of the pawls 37 10 and 39 are in engagement with the ratchet teeth upon the respective sides of the wheel 12.

A support 40 is rigidly mounted upon or formed integral with frame 7, said support carrying a bar 41. A bar 42 may be adjustably connected 15 to bar 41, said adjustable connection comprising a pin which passes through slots provided in each bar 41 and 42, which pin is threaded at its end and engaged with the hand wheel 43, the arrangement being such that bar 42 may be adjustably positioned along a portion of the length 20 of bar 41 and conversely bar 41 may be adjustably positioned along the length of bar 42 merely by manipulating hand wheel 43. Bar 42 carries a sleeve or bearing 43' at its lower end in which 25 a pin (not shown) is journaled. One end of said pin is rigidly connected to arm 44, the opposite end of which is pivotally connected to a palm 45. A spring 46 is associated with both the palm 45 and arm 44 in such a manner as to tend to rock palm 45 inwardly as viewed in Fig. 1.

Link 47 is rigidly connected to the pin which is journaled in the sleeve 43 and connects at its opposite end with link 48. Link 48 at its opposite end is pivotally connected to arm 49 which, in turn, is rigidly mounted upon shaft 50. Shaft 50 is journaled within bearings 51 which are carried upon downwardly extending arms secured to bar 41. An arm 52 is rigidly connected to shaft 50, the opposite end of said arm being pivotally 40 connected to link 53 which, in turn, is pivotally connected to arm 38 of the U-shaped member 35. The arrangement is such that lateral motion of the wire or screen 3 moves palm 45 in a similar manner. This movement rocks arm 44 which by 45 means of the various arm and link connections moves the member 35 either to the right or to the left as viewed in Fig. 1, depending upon the lateral shift of the wire or screen 3. It can readily be seen that when the link 53 moves the member 50 35, it will bring either pawl 37 or pawl 39 into contact with one of the faces of the ratchet wheel and inasmuch as the member 35 is reciprocating in a substantially vertical direction, said ratchet wheel will be rotated either upwardly or downwardly as viewed in Fig. 1. This movement will result in movement of the wheel along the length of the screw 11 and, consequently, block 15, journal box 20 and bearing 22 will be moved either to the right or left as the case may be.

55 A collar 50' is rigidly secured to shaft 50 and one end of a coil spring 51' circumscribes said shaft, the opposite end of said spring bearing against bearing 51. During the operation of the machine, palm 45 is normally disposed adjacent the edge of the wire or screen 3, spring 51' being normally under a slight tension. If the wire shifts laterally toward the palm, the various levers and arms hereinbefore described are moved whereby the U-shaped member is appropriately moved. 60 Simultaneously, spring 51' is wound up upon shaft 50. If the movement of the wire is excessively rapid whereby the shifting mechanism cannot keep up therewith, spring 46 upon palm 45 is flexed preventing injury to the wire by the 65 palm or vice versa. If the wire moves laterally 70 75

away from the palm spring 51' causes a reverse shift of the levers and arms and moves the U-shaped member to restore the wire to its normal path.

At the opposite side of the machine the shaft 54 of roll 23 is journaled in bearing 55. Bearing 55 is, in turn, carried by collar 56 which is pivotally connected at 57 and 58 to the frame 59 which latter is rigidly connected to frame 10. Consequently, when the bearing 22 is moved to the right or left as viewed in Fig. 1, bearing 55 will rotate in a vertical plane and the axis of roll 23 10 will be moved to a different transverse angle with respect to the longitudinal axis of travel of the wire or screen 3. By this arrangement if for some 15 reason screen 3 shifts laterally, the mechanism hereinbefore described will act to change the relations of roll 23 to screen or wire 3 so that said screen or wire will be shifted in the opposite direction. By this arrangement an equilibrium is 20 brought about whereby the wire or screen 3 is maintained traveling in a substantially true direction.

For roll 23 to have its highest efficiency and sensitivity in altering the direction of travel of 25 wire or screen 3, it is desirable that a predetermined constant pressure between said roll and the wire or screen be maintained. In addition, it is desirable that the tension of the screen or wire 3 be maintained at a predetermined value 30 for most efficient operation of the paper making machine itself. Therefore, a salient feature of my invention resides in a device which automatically satisfies both conditions, that is, it automatically maintains the wire or screen at a 35 predetermined degree of tension and accomplishes this at a point of travel of the wire or screen where the constant alignment of the screen is maintained and controlled.

Sleeve 4 carries an extension 60 which projects 40 in an opposite direction to the extension 6. Similarly sleeve 5 carries a projection 61 which extends oppositely to the projection 6. A recess 62 is provided in the projection 60 and a similar recess 63 is provided in the projection 61.

Cylindrical supports 64 and 65 are mounted at 45 each side of the machine adjacent pillars 1 and 2 respectively. Each support 64 and 65 carries a capstan 66 at its upper end which are rotatably mounted with respect to the supports. A screw 50 67 threadedly engages with the capstan 66 and is adapted to extend into the interior of the support 64. A similar screw, not shown, is associated with the support 65 at the opposite side of the machine. A bearing 68 is carried at the upper 55 end of screw 67 and similarly a bearing 69 is carried at the upper end of the screw at the opposite side of the machine.

A shaft 70 is journaled at each of its ends in 60 bearings 68 and 69. An arm 71 is rigidly connected to shaft 70 adjacent bearing 68, said arm being provided with a curved head 72 which is adapted to be positioned in the recess 62 in the projection 60. An arm 73 similar to arm 71 is also provided with a head 74 similar to the head 65 72 and it is adapted to extend into the recess 63 provided in projection 61. A pair of transversely spaced apart lever arms 75 are rigidly connected to shaft 70, adjacent the respective arms 71 and 73, and connected to the free end of each of said 70 arms 75 is a cable 76 which passes over a sheave wheel 77, the opposite end of the cables 76 carrying a predetermined number of weights 78.

The arrangement is such that the entire mechanism supporting roll 23, by virtue of the slidible 75

connection of the sleeves 4 and 5 with the pillars 1 and 2, respectively, would tend to be supported upon screen or wire 3. In view of the fact that this weight rests upon the inner surface of the loop comprising the forming wire, this weight would be constant and would not be sufficiently flexible to meet all of the conditions found in practice. Under some circumstances it may be desired to increase the tension of the screen in which case the weight of the roll 23 and its accompanying mechanism would not be sufficient. By the provision of the adjustable weights 78 and the mechanism associated therewith, the weight of the roll 23 and its accompanying mechanism may be augmented to substantially any desired degree and said weight may be maintained constant at substantially any selected value. It can readily be seen that the lever arrangement of arms 75, 71 and 73 is such that weights 78 augment the weight of the roll 23 and its accompanying mechanism, since arms 71 and 73 bear downwardly upon the lower defining wall of each of the recesses 62 and 63 and tend to slide the sleeves 4 and 5 downwardly along pillars 1 and 2. By the provision of the capstan 66 the height of the arms 71 may be accommodated to the height of the sleeves 4 and 5.

Although I have shown and described my invention in connection with a paper making wire or screen, it is apparent that it is equally applicable for use with the travelling felts or blankets of a paper making machine. In certain of the claims the term "belt" has been used in a generic sense, to cover the use of a reticulated wire screen, or a felt web. It is also manifest that my invention is capable of modification and rearrangement without departing from the spirit and scope of my invention. I do not, therefore, intend to limit my invention to the specific form and application

herein shown and described, except as indicated in the appended claims.

I claim as my invention:

1. In a paper making machine, an endless travelling flexible carrier, a pair of upright supports adjacent opposite edges of the return-run of said flexible carrier, carriages slidably mounted on said supports, a guide roll resting transversely upon the upper surface of the return-run of said flexible carrier, and having its ends supported by said carriages, whereby said roll is urged against the flexible carrier by its own weight and the weight of said carriages, means associated with said guide roll for maintaining the flexible carrier in longitudinal alignment, said means being responsive to transverse shifting of the flexible carrier for automatically shifting one end of said guide roll in a substantially horizontal plane to change its transverse position relative to the flexible carrier, and yielding means for urging the carriages downwardly in a vertical plane on said supports for maintaining the flexible carrier at substantially constant tension.

2. In a paper making machine of the type having an endlessly moving paper forming wire which makes an upper forward pass and a lower rearward pass, a guide roll resting upon the inner surface of said paper forming wire during its lower rearward pass, a pair of carriages from which said roll is suspended, a pair of vertical pillars positioned adjacent said carriages and upon which said carriages are slidably mounted, means for urging said carriages vertically downwardly along said pillars to augment the weight of said roll upon the wire, and means for shifting an end of said guide roll laterally relatively to one of said carriages.

WILLIAM C. NASH.
